CHRISTMAS TREE TOP ORNAMENT OR SIMILAR ARTICLE

Jack Burnbaum, 354 Dudley Road, Newton, Mass.

Filed June 17, 1963, Ser. No. 75,374

Term of patent 14 years

(Cl. D29—1)

Fig. 1.

Des. 198,751

PAGE 2

Fig. 2.

Fig. 3.

Fig. 4.

FIG. 1 is a front elevational view of a Christmas tree top ornament showing my new design;

FIG. 2 is a side elevational view looking from either the left or right of FIG. 1;

FIG. 3 is a top plan view; and

FIG. 4 is a bottom plan view thereof.

I claim:

The ornamental design for a Christmas tree top ornament or similar article, substantially as shown.
